UNITED STATES PATENT OFFICE

2,192,868

MULTICHAMBER FILTER PRESS

Edwin William Malkin, Fenton, Stoke-on-Trent, England, assignor of one-half to The Manor Engineering Company Limited, Fenton, Stoke-on-Trent, England, a British company

Application November 15, 1938, Serial No. 240,475

2 Claims. (Cl. 210—188)

This invention relates to improvements in multichamber filter presses in which a series of filter trays are individually suspended from an overhead girder runway by means of supporting rollers which cooperate with auxiliary guide rollers mounted on vertical spindles so as to be engageable with guide rails, and in which these filter trays are pressed together between a pair of similarly suspended end plates connected by longitudinal tie-rods; the primary object of the present improvements being to afford facilities for the exclusion of water or foreign matter from the upright bearings of the guide rollers, a secondary object being to facilitate the locking and unlocking of the tie-rods in relation to the filter trays and end plates for the closing and opening movements of the press.

These objects are attained by mechanism illustrated in the accompanying drawing, in which:

Fig. 1 is a front elevation of one end of a hydraulically-controlled multi-chamber filter press of the aforesaid kind having the present improvements applied.

Fig. 2 is an end elevation of the filter press, partly in section on a plane indicated by the line 2—2 in Fig. 1.

Fig. 3 is a fragmentary end elevation showing in sectional detail one of the auxiliary guide rollers and its vertical spindle mounting arrangements as improved in accordance with the invention.

Fig. 4 is a plan of the auxiliary guide roller and the retaining head of its vertical spindle as illustrated in Fig. 3.

Similar numerals refer to similar parts throughout the several views.

The framework of the multichamber filter press comprises an open pedestal 1 at each end, and a horizontal girder 2 centrally interconnecting the tops of the pedestals 1 to constitute an overhead runway. The series of filter trays 3 are pressed together between a pair of end plates 4 connected by longitudinal tie-rods 5, shown as three in number, each end plate 4 being suspended from the overhead runway by means of opposite pairs of supporting rollers 6 rotatable on the runway flanges of the girder 2 and supported by a pair of upstanding hangers 7, and the individual trays 3 being similarly suspended from the overhead runway by means of smaller supporting rollers 8 supported by upstanding hangers 9.

The supporting rollers 8 of the individual filter trays 3 are arranged in cooperation with auxiliary guide rollers 10 having ball-bearing mountings

11 on vertical spindles 12 fitted with sleeves 13 and upstanding from bracket arms 14 secured to the hangers 9, these guide rollers 10 being engageable with the inner faces of auxiliary guide rails 15 fixed longitudinally to opposite sides of the overhead runway girder 2 at a suitable spacing therefrom.

The upper face of each auxiliary guide roller 10 is outwardly inclined in a shallow conical form to facilitate drainage of water therefrom, and 10 is further formed with an upstanding annular flange 16 surrounding its central bore, the retaining head 17 of the vertical spindle 12 being formed with a dependent annular flange 18 which constitutes an enclosing hood for the flange 16 15 and thereby serves to ensure that both water and solid matter are excluded from the upright bearings of the auxiliary guide roller 10, this protective action being further ensured if desired by the provision of radial drainage channels 19 in 20 the inclined upper face of the guide roller 10.

The filter press as illustrated is adapted for hydraulic control by means of rams 20 operatively associated with the respective tie-rods 5, the series of hydraulic rams 20 being controlled in common from a pressure-distributing unit 21, and each tie-rod 5 being fitted at each end with a lock-nut 22 adapted for tommy-bar control, thereby facilitating both the locking of the tie-rods in relation to the filter trays 3 and end plates 4 as the press is tightened up, and also the unlocking of the tie-rods 5 for the opening of the press, independent of any manipulation of cotter-pins or the like.

It may be explained that the type of filter press to which the invention relates is designed for use mainly in the preparation of potter's clay, but is applicable also for analogous industrial purposes.

I claim:

1. In a multiple-chamber filter press of the overhead suspension type, a fixed vertical spindle provided with a retaining head, an auxiliary guide roller rotatably mounted on said spindle on antifriction bearings, an integral dependent 45 and annular hooding flange formed on the periphery of the head of the said spindle, an upstanding annular flange on the upper face of the said guide roller, the dependent flange freely embracing the upstanding flange for the purpose of 50 excluding moisture and solid matter from the said bearing.

2. In a multiple-chamber filter press of the overhead suspension type, a fixed vertical spindle provided with a retaining head, an auxiliary 55

guide roller rotatably mounted on said spindle on antifriction bearings, an integral dependent and annular hooding flange formed on the periphery of the head of the said spindle, an up-standing annular flange on the upper face of the said guide roller, the dependent flange freely em-

bracing the upstanding flange for the purpose of excluding moisture and solid matter from the said bearing, and channels formed in the upper inclined face of said guide roller to afford drainage facilities.

EDWIN WILLIAM MALKIN.
